UNITED STATES PATENT OFFICE.

CHARLES H. STORM, OF WATERLOO, IOWA, ASSIGNOR TO HIMSELF, RALPH L. STORM, EDWIN M. STORM, AND CHARLES S. CHASE, OF SAME PLACE.

AUTOMATIC SIGNAL FOR ELECTRIC RAILWAYS.

SPECIFICATION forming part of Letters Patent No. 674,523, dated May 21, 1901.

Application filed August 28, 1900. Serial No. 28,281. (No model.)

To all whom it may concern:

Be it known that I, CHARLES H. STORM, a citizen of the United States of America, and a resident of the city of Waterloo, Blackhawk county, Iowa, have invented certain new and useful Improvements in Automatic Signals for Electric Railways, of which the following is a specification.

My invention relates to automatic signals for electric railways; and it consists in the novel construction, combination, and arrangement of parts hereinafter described and claimed.

The object of my invention is to provide a system of signaling for such electric railways as are operated with a single track, so designed as to prevent collisions between cars when headed in opposite directions on any part of the line where for any reason a view of the track is obscured. I am aware that various forms of contact devices are in use, whereby pressure derived from the trolley-wheel on a car operates apparatus for lighting or extinguishing lamps or moving signals; but the particular object of my invention is to provide an apparatus so simplified in its construction as to minimize wear of the parts and whose contact devices are dependent upon gravity in regaining their positions when not otherwise in operation, thus doing away with the necessity of using springs, which will rust out, and always being certain in operation.

Reference is to be had to the accompanying drawings, wherein similar letters of reference indicate corresponding parts in all the several views.

Figure 1 is a side elevation of one of the signaling devices with its connections as used at one end of a section. Fig. 2 is a top plan view of the same. Fig. 3 is a side elevation of the form of signaling device as used at the other end of the section. Fig. 4 is a top plan view of the same. Fig. 5 is a diagrammatic view of a pair of the signaling devices as used at both ends of the block or section of railway-track, showing method of operation.

P represents a single track having turnout-tracks at either end of the section. To the trolley-wire Z at any suitable locations

near the ends of the section are attached, by means of the insulators T T, the contact signaling devices, which are also supported from a suitable point above by guy-wires T' T'. A frame A, which is hung on the insulators T T, is provided with openings through which the gravity-plungers C and G move vertically. Each of these plungers move on slideways over studs fixed on the inner sides of the openings, as indicated by the dotted lines at H and H'.

The releaser-plunger C is provided with a metallic cap D, whose ends extend over and are bent down over the sides of the plunger a sufficient distance to bring them into contact with conductors E and E'.

To the binding-post O', which passes through the conductor E', is connected the wire M, and the latter is brought into electrical contact with the trolley-wire Z. Normally when there is no car on the section the plunger C, drawn by gravity, is in the position shown in Fig. 1, having the ends of the metallic plate D in contact, respectively, with the conductors E and E'.

The plunger G moves vertically upon slideways over studs H' in a similar manner to that of the plunger C and is constructed, as is C, with its lower head shaped in an elliptic curve. This head has extensions beyond the shank to keep the movement of the plunger within proper limits.

Each plunger G is, like each plunger C, raised by the passage of the trolley-wheel beneath it; but while the plungers C drop back by gravity the plungers G are held in elevated position by their electromagnets J, which are thrown into circuit by contact of the conductors L L', which is effected when the plungers G are raised.

F represents a box attached to the upper surface of the frame A, its lower opening registering with the opening in the frame in which the plunger G moves. Upon the top of the box F is fixed the electromagnet J, its pole-piece I passing through a perforation in the box and extending a short distance below.

In the middle of the top surface of the plunger G is embedded an armature K. Fas-

frame A, is a metallic band L', forming a conductor, and to which is attached the end of the wire U by means of a binding-post.

L represents a metallic band fastened at 5 one end to the upper surface of the frame A near the box F, and which band is bent into a form which leaves its free end impending over the conductor L' and but a short distance above it. The conductor L has communication with the electromagnet J by 10 means of the wire R. When the section P is clear, the plunger G, drawn by gravity, falls into the position shown in Fig. 1, disconnecting the conductors L and L', the circuit being broken between the trolley-wire Z and the lamps, leaving them unlighted.

Y, Y', and Y² are feed-wires designed as 15 means of communication between the separate signal devices at the ends of the section. 20 The wire N connects the releaser C with the feed-wire Y', while the electromagnet J has a wire S extending from the upper part of its coil to the lamps W W. The wire Y² operates to conduct the current from the lamps 25 W to the ground.

The wire U forms a means of communication between the post O on the plunger C and the conductor L' on the plunger G.

V and X are wires connecting the lamps W 30 W with the feed-wires Y² and Y, respectively.

In operation the apparatus is made effective as follows: When a car is about to enter a single-track section, as at P, moving in the direction 2, the quiescent apparatus is not 35 affected when the trolley-wheel Z' passes under and raises the plunger C, as C, drawn back by gravity, reestablishes circuit through D, E, and E'. When the trolley-wheel in turn passes under and lifts the plunger G, said 40 plunger remains in an elevated position and is held there by reason of the magnetic attraction between the excited electromagnet J and its armature K. The current from the feed-wire M is now passing through the 45 electromagnet J. As the conductor L' is brought, by reason of its elevation with the plunger G, into contact with the free end of the bent conductor L the current passes thence through wire R to the electromagnet 50 J. The lamps W W and W² W² are thus lighted by current from trolley-wire now passing directly through wire M and its connections at E, the wire U, conductors L' and L, the electromagnet J, wires S, and thence by 55 wires X, Y, and V' to lamps W² W², wire X', through conductors E² D' E³ X² to ground. As the car moves on, all the lamps remain lighted until the car passes from the section and the trolley-wheel Z' impinges upon the 60 releaser C'. When the releaser C' is raised, the circuit is broken between the conductors D', E², and E³; and the armature K is released by the electromagnet I J, the plunger G dropping back into position by its gravity, and 65 the lights in signal-lamps at W W and W² W² are extinguished, signifying to a motor- 70 neer approaching from an opposite direction

that the section is clear ahead. In case a car is entering the section P, moving in the direction 1, the section being clear and lamps 75 unlighted, the operation of the signaling device is similar to that already described, except that the current for lighting the lamps is derived in the following manner: The establishing of electrical communication by the 80 contacts of the conductors L² and L³ brings the current first from the trolley-wire by wire M, conductors E', D, and E, wires N Y' N', conductors L² and L³, wire L⁴, electromagnet J', wires S' Y² V to lamps W W, thence by 85 wires X Y V' to lamps W² W², thence by wire X' to conductors E² D' E³ and wire X² to ground. Semaphore or bell signals may be connected with this system, if desired.

Having thus described my invention, what 85 I claim as new, and desire to secure by Letters Patent, is—

1. In an automatic signal for electric railways, the combination with an electric generator and a trolley-wire; of a frame having 90 openings, gravity contact-plungers movable vertically in said opening and adapted to be actuated by a trolley-wheel, armatures on said plungers in circuit with electromagnets above the trolley-wire, gravity releasing-plungers movable vertically in other openings in said frame and provided with contact-conductors adapted to move vertically when actuated by the pressure of a trolley-wheel and break the electrical circuit through the conductors, conductors for carrying a current from the trolley-wire to the releasing and contact plungers and thence to and from signal-lamps, signal-lamps situated at either end of a 95 section of track, in circuit with the gravity contact-plungers, means for grounding the current from the signal-lamps, trolley-actuated mechanism for elevating the gravity-plungers, with suitable connections and supports, substantially as shown and described. 100

2. In an automatic signal for electric railways, the combination with the trolley-wheel, the trolley-wire connected with a suitable electric generator, signal-lamps connected with each other and with the ground and located at each end of a track-section, and a frame held on insulated supports above each end of said section; of two plungers movable vertically in each frame and raised by the trolley-wheel but adapted to fall by gravity, 115 an electromagnet above one plunger, two normally-separated conductors of which one is in circuit with the coils of this magnet and the other is connected with the plunger-body, two conductors adjacent the other plunger, a 120 bent plate carried by its body and normally forming a circuit between these conductors; and electrical connections forming a circuit from the trolley-wire, through both plungers of one frame, then through the lamps, then 125 through the plunger of the other frame which carries the bent plate, and to the ground, all substantially as described. 130

3. The combination of the trolley-wire Z,

the frame A, wires T', insulators T, the gravity contact-plunger G adapted to move vertically over studs in slideways H, the armature K embedded in non-conducting material in the upper portion of the plunger G, the conductors L and L', the box F, the electromagnet I J, the wires R, S and U, the releasing gravity-plunger C adapted to move vertically within an opening in frame A over 5 studs in the slideways H', the conductors D, E and E', the binding-posts O and O', the box B, the wires M and N, the feed-wires Y, Y' and Y², the lamps W, the wires X, V, V' and X', the lamps W² W², the wires S', N', electromagnet I' J', box F', plunger G', armature K' embedded in non-conducting material in the upper portion of the plunger G', conductors L², L³, wire L⁴, ground-wire X², releasing gravity-plunger C', box F', conductors 10 D', E² and E³, frame A' and track P, substantially as shown and described.

4. The combination of the track P, trolley car and wheel Z', electrical generator Z², trolley-wire Z, wires T', insulators T, frame A, 15 box B, releasing-plunger C, stud and slide- ways H, conductors D, E and E', binding-posts O and O', wires M, N and U, contact-plunger G, stud and slideways H', electromagnet I J, armature K embedded in non-conducting material in the upper part of the 20 plunger G, conductors L and L', box F, wires R and S, feed-wires Y, Y' and Y², lamps W, W and W² W², conducting-wires V, X, V', X', N', S', L⁴ and X², frame A', gravity releasing-plunger C', studs and slideways H², conductors D', E² and E³, binding-posts O² and O³, box B', gravity contact-plunger G', electromagnet I' J', armature K' embedded in non-conducting material in the upper portion of the gravity contact-plunger G', the studs 25 and slideways H³, the conductors L² and L³, and the box F', with suitable connections and supports, substantially as shown and described.
